UNITED STATES PATENT OFFICE.

EMMETT P. RYBURG, OF KANSAS CITY, MISSOURI, ASSIGNEE OF ONE-HALF TO ADOLPH LOTZ, JR., OF EUDORA, KANSAS.

CONTAINER CAP.

Application filed September 23, 1922. Serial No. 590,155.

To all whom it may concern:

Be it known that I, EMMETT P. RYBURG, a citizen of the United States, residing at Kansas City, in the county of Jackson and 5 State of Missouri, have invented certain new and useful Improvements in Container Caps, of which the following is a specification.

My invention relates to closures for containers and while it may be used for general purposes it is more particularly adapted for the filler openings of automobile radiators and gasoline tanks.

One important feature resides in the 15 quick manner in which the device may be opened for the introduction into the container of water, gasoline, or other liquid, and the rapid manner in which said device may be closed after such introduction, such 20 opening and closing movements being accomplished in much less time than is possible with the screw caps usually employed.

Another feature resides in the fact that 25 there are no removable parts to become lost as in the case where removable screw caps are employed.

Other features will hereinafter appear and 30 in order that the invention may be fully understood, reference will now be had to the accompanying drawings, in which:

Fig. 1 is a broken plan view of one form 35 of the device in closed position and applicable to the filler openings of automobile radiators.

Fig. 2 is a plan view of the device in open position.

Fig. 3 is a vertical cross section on line III—III of Fig. 1.

Fig. 4 is a detail plan view of a segmental 40 plate.

Fig. 5 is a plan view of a form of the device applicable to the gasoline tank of an automobile, the device being in closed position.

Fig. 6 is a plan view of the last-mentioned 45 device in open position.

Fig. 7 is an irregular vertical cross section on line VII—VII of Fig. 5.

Fig. 8 is a reduced plan view of an inner 50 plate.

Referring now more particularly to the form disclosed by Figs. 1 to 4, inclusive, 2 designates a tubular member provided with threads 4 at its lower portion so that it may 55 be screwed upon the neck of the filler open-

ing of a container, such, for instance, as a radiator (not shown) in place of the usual screw cap. While I have shown internal threads 4 it is to be understood that the tubular member 2 may be externally 60 threaded should the neck of the filler opening be internally threaded.

The upper portion of the tubular member 2 is provided with an integral plate 6 having an opening 8, which is normally closed 65 by a cap 10 rotatably mounted upon said plate 6. The cap 10 consists of a top plate 12 and a depending marginal flange 14, which latter snugly but rotatably embraces the upper peripheral portion of the tubular 70 member 2 and assists in holding said cap 10 in position. The plate 12 has an opening 16 adapted to register with the opening 8 when the cap 10 is opened by rotating a half revolution in the direction of arrow *a* Fig. 1, to 75 the position disclosed by Fig. 2. The rotary movement of the cap 10, to open and close the device, is limited by a stop 18 extending downwardly through the top plate 12 and into the path of the ends of the opening 8 in 80 the plate 6.

20 designates a segmental plate which bears against the underside of the plate 6 and is connected to the top plate 12 of the cap 10 by means of the stop 18 and a tubular rivet 22, which latter extends through axial openings in the plates 6, 12 and 20, as more clearly shown by Fig. 3.

In some instances the rivet 22 may be solid but I prefer to make it tubular as 90 shown and described, so that a motometer or an ornamental device can be readily installed on the device. Before shipping the device from the factory the tubular rivet 22 is closed by a plug 24 removably held in 95 place by a nut 26, so that said plug 24 may be readily removed in case a motometer or an ornamental device is to be installed as above stated. The plug 24 is provided with a removable bushing 28 to fit the stems of motometers or other devices having stems too small to snugly fit the opening through the rivet 22.

The segmental plate 20 assists in holding the cap 10 snugly upon the plate 6 of the 105 tubular member 2 and also in preventing any dust which might work through the openings 8 and 16 when the cap 10 is closed, from passing downwardly through said tubular member 2 and entering the container to which it 110

is connected. The plate 6 has a circular groove 30 formed in the upper surface thereof, so that any dust entering between said plates 6 and 12 will pass into said groove 30 and 5 thus in a manner form a gasket which will coat with the plate 20 in preventing dust from passing downwardly through the tubular member 2.

For convenience in rotating the cap 10 10 to open and close the device I provide said cap with oppositely-disposed handles 32, which may be of plain or ornamental design. In some instances the segmental plate 20 may be dispensed with, in which case the 15 lower flange of the tubular rivet 22 would be made to engage the undersurface of the plate 6, but I prefer to employ said segmental plate 20 as it assists in holding the cap 10 upon the tubular member 2 and in 20 excluding dust, as above set forth.

In order to prevent the device from being stolen when installed on the filler opening of a container, I provide the tubular member 2 with a threaded lateral opening 34 for 25 the reception of a set screw 36, which may be screwed tightly against the neck of the filler opening to lock said tubular member 2 in place. The set screw 36 is shorter than the opening 34 as shown, so that when 30 screwed against the neck of the filler opening as stated its outer end may be concealed by a suitable plug forced within the opening 34.

The form disclosed by Figs. 5 to 8 inclusive, is designed more particularly for use 35 on the filler openings of gasoline tanks (not shown). Said form embodies a tubular member 2^a having an upper plate 6^a provided with an opening 8^a. The lower portion 40 of the tubular member 2^a has threads 4^a for engaging the threads of the filler opening of a gasoline tank in lieu of the screw cap usually employed for that purpose. Said tubular member 2^a also has an internal 45 flange 4^b adapted to engage the upper margin of the neck of the filler opening.

The opening 8^a is normally closed by a cap 10^a having a thumb piece 10^b, which may be readily grasped with the thumb and forefinger preparatory to moving the cap 10^a to open or closed position. The cap 10^a is provided with a fixed pivot 22^a, which has a round portion 40 journaled in the plate 6^a and a rectangular portion 42 to fit into the 55 corresponding opening 44 in a circular plate 46 against the underside of which the lower end of the pivot 22^a is upset to hold the cap 10^a and the plate 46 together. The rectangular portion 42 of the pivot 22^a passing through the corresponding hole 44 in the plate 46, causes the latter to rotate with the cap 10^a when the same is swung to open or closed position.

The plate 46 is provided with an opening 60 48, which registers with the opening 8^a when

the cap 10^a is swung to open position. The movement of the cap 10^a and the plate 46 is limited by lugs 50 on the plate 46, which alternately contact a lug 52 formed inside the upper portion of the tubular member 2^a. 70 A vent 54 is provided in the plate 46 to admit air when the device is installed on the gasoline container of a motor vehicle, so that the vacuum feed system with which most cars are equipped may properly function. Air to the vent 54 is admitted through the opening 8^a and the joint between the closed cap 10^a and the top 6^a, which joint however is sufficiently tight to practically exclude all dust. The tubular member 2^a like the tubular member 2 may be secured from theft by means of a set screw 36^a. 80

The operation of opening and closing the device is very simple. In order to open the device the member 10^b is grasped and the cap 10^a swung from the position disclosed by Fig. 5 to the position disclosed by Fig. 6, to uncover the opening 8^a. As the plate 46 is caused to rotate with the cap 10^a through the intermediacy of the pivot 22, the opening 48 is brought into coincidence with the opening 8^a, so that gasoline may be readily supplied to the container through the tubular member 2^a. The device is closed by moving the cap 10^a to the position disclosed by 90 Figs. 5 and 7, which movement causes the solid portion of the plate 46 to pass beneath the opening 8^a and thus coat with the cap 10^a in preventing the passage of dust through said opening 8^a. 95

From the foregoing description it will be readily understood that I have provided devices embodying the advantages above pointed out, and while I have shown two forms of such devices I reserve the right 105 to make such other forms as properly fall within the spirit and scope of the claims.

Having thus described my invention, what I claim and desire to secure by Letters Patent, is:

1. In a device of the character described, a tubular member adapted to be connected to a container and provided with an upper plate having an opening therein, a second plate bearing against the underside of said upper plate and adapted to open and close the opening therein, a third plate arranged on top of the upper plate to coat with said second plate in opening and closing the opening in said upper plate, and means connecting the second and third plates to cause them to operate in unison. 115

2. In a device of the character described, a tubular member adapted to be connected to a container and provided with an upper plate having an opening therein, another plate associated with said upper plate to open and close the opening therein, and a tubular member for holding said plates together. 125

3. In a device of the character described, a tubular member adapted to be connected to a container and provided with an upper plate having an opening therein, another plate associated with said upper plate to open and close the opening therein, a tubular member for holding said plates together, and a removable plug to close the opening through said tubular member.
- 10 4. In a device of the character described, a tubular member adapted to be connected to a container and provided with an upper plate having an opening therein, a second plate bearing against the underside of said upper plate and adapted to open and close the opening therein, a third plate arranged on top of the upper plate to coact with said second plate in opening and closing the opening in said upper plate, an axial member for holding the second and third plates 20 in proper relation to the upper plate, and means extending through the opening in the upper plate to connect the second and third plates to cause them to operate in unison and limit their opening and closing movements by contacting the ends of the opening in the upper plate.
- 15 In testimony whereof I affix my signature in the presence of two witnesses.

EMMETT P. RYBURG.
